US0D1101009S

(12) **United States Design Patent** (10) Patent No.: **US D1,101,009 S**
(45) Date of Patent: ** Nov. 4, 2025

(54) **HEAT PRESS**

(71) Applicant: **Cricut, Inc.**, South Jordan, UT (US)

(72) Inventors: **Yung Tseng Chen**, San Francisco, CA (US); **Thomas Crisp**, Cottonwood Heights, UT (US); **John Douglas Dalton**, South Jordan, UT (US); **Michelle Fishberg**, San Francisco, CA (US); **Desmond Kavanagh**, Wicklow (IE); **Hayley Ketch**, Alpine, UT (US); **Michael Nolan**, Dublin (IE); **Ildefonso M. Resuello, Jr.**, Sacramento, CA (US); **Norman Stevenson**, Dublin (IE); **Grayson Stopp**, San Francisco, CA (US)

(73) Assignee: **Cricut, Inc.**, South Jordan, UT (US)

(**) Term: **15 Years**

(21) Appl. No.: **29/879,583**

(22) Filed: **Jul. 10, 2023**

Related U.S. Application Data

(63) Continuation of application No. 29/792,102, filed on Mar. 3, 2022, now Pat. No. Des. 991,989.
